CLAIM

The ornamental design for a pole mountable shower shelf with mesh sidewalls and curved face cloth bar, as shown and described.

DESCRIPTION

FIG. 1 is a perspective view of a pole mountable shower shelf with mesh sidewalls and curved face cloth bar in accordance with my design, and with the curved sidewall defining the front of the shelf and the right-angle corner defining the rear of the shelf;

FIG. 2 is an elevational view of the right rear wall of the shelf shown in view FIG. 1, with the left rear wall being a mirror image thereof;

FIG. 3 is a front elevational view of the shelf shown in FIGS. 1 and 2;

FIG. 4 is a rear elevational view of the shelf shown in FIGS. 1-3;

FIG. 5 is a top plan view of the shelf shown in FIGS. 1-4; and, FIG. 6 is a bottom plan view of the shelf shown in FIGS. 1-5.
